(57) **CLAIM**

A grip for cooking utensils, as shown and described.

DESCRIPTION

FIG. 1 is a top perspective view showing a grip for cooking utensils in accordance with the present invention mounted in each handle of a first representative cooking utensil;

FIG. 2 is a top plan view of the grip and utensil of FIG. 1

FIG. 3 is a side elevational view thereof;

FIG. 4 is an end elevational view thereof;

FIG. 5 is a bottom plan view thereof; and

FIG. 6 is second top perspective environmental view;

FIG. 7 is a third top perspective environmental view;

FIG. 8 is a fourth top perspective environmental view; and,

FIG. 9 is a fifth top perspective environmental view.

The broken lines are for illustrative purposes only and form no part of the claimed design.
